Primary Examiner — Wan Laymon*Assistant Examiner* — Mark Booker(74) *Attorney, Agent, or Firm* — Bereskin & Parr LLP/S.E.N.C.R.L., s.r.l.(57) **CLAIM**

I claim the ornamental design for a height-adjustable furniture piece, as shown and described.

DESCRIPTION

FIG. 1 is a front perspective view of the height-adjustable furniture piece in accordance with our new design, where the height-adjustable furniture piece is shown connected to a wall.

FIG. 2 is a left side view thereof;

FIG. 2A is an enlarged view of the portion within the dash-dot line box shown in FIG. 2;

FIG. 3 is front view thereof;

FIG. 4 is right side view thereof;

FIG. 5 is a top plan view thereof; and,

FIG. 6 is a bottom plan view thereof.

The broken lines in the figures are to illustrate environmental structure only and form no part of the claimed design. The dash-dot lines in the figures are to illustrate boundaries and also form no part of the claimed design.
